CLEANSER-SAVING HOLDING DEVICE

Florence Bisignano, Elmhurst, N. Y.

Application April 7, 1949, Serial No. 86,059

1 Claim. (Cl. 45—28)

1.

This invention relates to new and useful improvements in a device of the holder class for use in connection with the storage and/or handling of cleansers and detergents, and, more particularly, the aim is to provide a novel and valuable such holder for advantageous employment for conveniently supporting a cleansing or detergent agent or the like, as between uses thereof and/or at intervals during a period while said agent is manually in use as by a housewife; the new device being of special utility when said agent is a "Brillo"-type or steel-wool-mass-including or equivalently abrasive entity, and hence by virtue of the fact that ordinarily in the use of said agent a soapy substance is present calling for the use therewith of a fairly heavy content of water as a contributor to efficient action. The invention, however, is not to be limited to utilization in connection with such steel wool or the like; the cleansing or detergent agent could be, for example, a bar or cake soap.

An object of the invention is to provide a means for utilizing the accumulated drippings from the detergent which discharge into the lower cup-like receptacle.

By the present invention, the combination is provided of an upper cup-like receptacle having water-drain openings at its bottom, this for holding said agent, a lower cup-like receptacle, this for accumulating the water drippings discharged through said openings, and means including a post-like permanently incorporated connector for said cups and pivotally carrying the upper cup and shaped and arranged in such manner that (a) the upper cup may be so positioned, when it is to store or temporarily hold the said agent, that any and all of said drippings must fall into the lower cup, (b) said upper cup is then so placed that instantaneously and easily said agent may not only be deposited therein but removed therefrom, (c) due to the general construction, such pivotal means is so present as to allow the upper cup, as at the end of a use of said agent, to be swung about a horizontal axis through substantially 180° or less, thereby sufficiently to move said cup toward inverted position that said agent may drop by its own weight from said cup and beyond the top open mouth of the lower cup, and (d) the parts are all so correlated that with the upper cup in either of its extreme positions of swing, the device as a whole will be in stable equilibrium for resting by its own weight and on its bottom on a table top, shelf or other suitable support.

For further comprehension of the invention, 55 posed as shown in full lines, that is, with the

2.

and of the objects and advantages thereof, reference will be had to the following description and accompanying drawings, and to the appended claim in which the various novel features of the invention are more particularly set forth:

In the accompanying drawings forming a material part of this disclosure:

Fig. 1 is a view in side elevation, partially broken away and partially in section, illustrating a now favored embodiment of the invention; with the upper cup shown in full lines as in normal operative relation to the lower cup, and with said upper cup shown in broken lines as inverted because of swing through about 180°.

Fig. 2 is a view similar to Fig. 1, but illustrating another now favored embodiment.

Fig. 3 is a top plan view of the device of Fig. 2.

Fig. 4 is a perspective view for showing more clearly the post-like connector of Figs. 2 and 3.

Referring to the drawings now in detail, and first to Fig. 1, the two cups are desirably as indicated cylindrical open-top receptacles. The upper cup 15 has a perforated bottom wall 16, which perforations provide the drip openings already mentioned. As here shown, the wall 16 is surrounded by a depending skirt portion for facilitating permanent fixation of said wall near the bottom of the cylindrically tubular member or structure providing the side wall of the cup 15. Said bottom wall 16 may be a plane disc, reticulated or made foraminous in any way, or a wire mesh or a grid of any kind, attached in any suitable way, as by soldering, in and to the upper cup 15.

The already mentioned lower cup 17, having all its walls water-tight, is desirably provided with an outwardly flared ring portion 18. Said lower cup may well be spun from one piece of sheet material, if made of metal; while it may readily be molded, if made of plastic.

The already mentioned permanent connecting means 19 for the cups 15 and 17 may be in the form simply of (a) a post-like member 20, which may comprise merely a cut-off length of strip metal or plastic stock, of standard width and thickness, but given a bend as indicated at 21, and (b) a hinge 22, this consisting as here shown of a pair of hinge plates and a coupling pintle, with one of said plates suitably secured at its leaf portion to the upper exterior of the cup 15, and the other of said plates suitably secured at its leaf portion to the upper end of the member 20 at the side thereof remote from the cup 15.

It is to be noted that when the parts are dis-

aforesaid agent and any water content thereof in addition to its soap content, placed in the cup 15, said agent is adequately retained and yet water drippings may pass through the perforations in the bottom wall 16, all for certain accumulation in the cup 17. When such dripping has ceased, and the said agent is sufficiently dried, the cup 15 may be swung to or toward the inverted position indicated at 15A, for drop therefrom, as onto a suitable auxiliary receptacle, 10 of the said agent. Further, with the cup 15 as last described, the soapy residue settling in the bottom of said cup may be readily reused.

Referring to the modification shown in Figs. 2-4, the parts to which are applied reference characters with primes added correspond, respectively, to the parts to which have been applied the same reference numerals but without primes. Here the upper cup 15' in its full-line position has its bottom wall 16' inclined to the horizontal, and it has its top mouth generally in a plane which converges, in a direction away from the hinge 22' toward the plane containing said wall 16'. According to this arrangement, while a safe retainer for the said agent is presented, manual withdrawal of said agent from the cup 15' is much facilitated, it being noted that said rim, at a point opposite the hinge 22', has a forefinger-admitting depression. Also, in the form of the invention now being described, the post-like member 20' has its bend 21' a single bend, and not a double reverse bend as in the case of the bend 21. At said bend 21', the member 20' is laterally shaped to provide a furrow 23 to act as a drip channel relative to any water dropping down from the cup 15' onto said member 20'; whereby all water drippings originating at the perforations in the wall 16' must fall into the cup 17'. Further, in the form of the invention now being described, the hinge 22 is partially comprised of a pair of curls 24 on the top of the member 20', and a curl 25 integrally carried by the cup 15', together with a pivot pin 26 similar to that used in connection with the structure of, and shown in, Fig. 1.

With the parts arranged as shown in full lines in Fig. 2, said agent may be safely received in the cup 15', and when it is desired to remove said agent, its removal is facilitated without having to dip the hand of the housewife deep into said cup and, indeed, said agent may be removed following merely the insertion of one of her fingers through the depression already mentioned, this designated 27. The device of Figs. 2-4, as will

be noted, has all the other utilities described in connection with the device of Fig. 1.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

Means supporting an upper cup having a cylindrical side wall and a perforated bottom wall 15 in a position suspended over a bottom cup having a cylindrical side wall, comprising a vertically extended elongated member having its bottom end portion secured in position along the inner face of the side wall of the bottom cup, said member having its top end portion extended along the outer face of the side wall of the upper cup, means attaching the upper cup to the top end portion of said member, said member having a bend intermediate of its ends and 25 between said cups so that the top end portion of said member is inclined upward and away from the bottom cup to support the top cup with its perforated bottom inclined downward and toward said member to drain water in the upper cup to the low side of the perforated bottom wall where it will drop onto said elongated member below the upper cup, and a vertically extended reinforcing furrow formed in said member at said bend and directed away from said cups forming a vertically extended channel beneath the low side of the perforated bottom wall 30 to catch water as it drops from the upper cup onto the elongated member and direct that water into the lower cup.
